HOT CATHODE TUBE WITH METAL ENVELOPE

Erwin F. Lowry, Forest Hills, Pa., assignor to Westinghouse Electric & Manufacturing Company, East Pittsburgh, Pa., a corporation of Pennsylvania

Application January 4, 1936, Serial No. 57,537

9 Claims. (Cl. 250—27.5)

This invention relates to gas-filled discharge tubes and particularly to such tubes having a metallic envelope.

It is an object of this invention to provide an arrangement of the tube electrodes in which the two principal electrodes are electrically separated from one another by the seal which joins the two main parts of the envelope.

It is a further object of this invention to so arrange the electrode that spacings may be closer and the structure more rigid than heretofore.

It is a further object of this invention to make use of a directly heated cathode structure, having an electrostatic guard to produce delayed action, and to support such structure by a metal plate through which the cathode is electrically united with a portion of the envelope.

It is a further object of this invention to utilize a cathode structure which extends substantially across the whole diameter of the tube and electrically to unite such structure with the envelope.

It is a further object of this invention to provide a seal made of several parts of different insulating material and to prolong the innermost part into a skirt within the tube, thereby affording a long creepage path within the tube between the two main electrodes.

It is a further object of this invention to provide a seal including several insulating materials, at least one of which makes a sealing union with the metal of the envelope.

It is a further object of this invention to provide a duct for pumping the tube which also serves as a conductor to one of the electrodes.

Other objects of the invention and details of the structure will be apparent from the following description and the drawing in which:

Figure 1 is a vertical section through one form of my device;

Fig. 2 is a similar section through a modification; and

Fig. 3 is a similar section showing another application of the device.

In Fig. 1, a part 1 of the envelope constitutes the anode and the cathode is electrically united to another part 2 of the envelope. Between the parts 1 and 2 are two rings 3 and 4, the ring 3 being welded to the part 1 and the ring 4 to the part 2. Each ring comprises a portion contacting the edge of the adjacent part, 1 or 2, of the envelope and a flange contacting the outer surface of that part adjacent the edge. At either or both places the contacting surfaces may be welded together. The parts 1 and 2 may be of any convenient metal, preferably steel, and the rings 3 and 4 are of an alloy which can be wetted by molten or softened glass, and which will have substantially the same coefficient of expansion as the glass. It is also desirable that

the alloy selected be unaffected by the vapor in the tube, especially when hot.

Between the rings 3 and 4 a glass flange 5 is integral with a sleeve 6 of the same material is interposed. The sleeve 6 forms a skirt within the tube depending from the seal and making a long leakage path separating the parts 1 and 2. The flange 5 is sealed to the rings 3 and 4. If preferred, the sleeve 6 and its flange 5 may be of refractory ceramic material and a body 10 of glass of the kind just described may be inserted in contact with the outer end of the flange 5. Outside of it, but with its inner part between the rings 3 and 4, a body 11 of refractory ceramic material may be placed in contact with the rings 15 3 and 4 and with the glass 10. The outer part of the body 11 is extended over the outside surfaces of flanges upon the rings, thereby affording a long leakage path on the outside of the tube between portions 1 and 2 of the envelope.

An alternative structure may be chosen in which the part 10 is refractory ceramic material and the parts 5 and 11 are glass. With either structure, the sealing may be accomplished by placing the completed tube in an oven and heating it to the point at which the glass softens or partially fuses, causing the glass portion to wet not only the rings but also the adjacent ceramic refractory parts making the whole seal a gas-tight structure.

For this method of sealing, it is preferable that the central portion 10 be the glass portion. The ceramic parts 5 and 11 then act as stoppers confining the glass while it is liquid or soft and also maintain the spatial separation between rings 3 35 and 4 while the glass is safe.

It is also possible to omit the parts 10 and 11, in which case the part 5 must be of glass.

A seal may be made at the center of the part 1 and through it a conductor 15 extends to the grid 40 16. The seal for the lead 15 is in the center of a ring 17 of metal which will form a good seal with the glass. This ring is welded to the adjacent portions of the part 1. It comprises a sleeve extending into the interior of the tube and 45 a flange overlapping the outside of the part 1.

The seal comprises a portion 18 of glass forming a sealing contact both with the conductor 15 and with the inwardly extending sleeve of the ring 17. Inside of the tube the portion 18 is 50 expanded, forming a skirt 19 which extends nearly into proximity with the grid 16. The skirt makes a long creepage path between the part 1 and the conductor 15.

The glass extends beyond the outer surface of 55 the ring 17 but not very far because it must not be exposed to the danger of being hit and broken. The distance to which the glass extends above the ring depends on the necessary leakage path to properly insulate the grid 16 from the anode 1. 60

The metal sleeve, extending well along the glass inside the tube, adds to the rigidity of the structure and can extend so far because the skirt 19 affords sufficient insulation in the comparatively short distance.

The grid 16 is spaced slightly from the end of the skirt, whereby the inner and outer surfaces of the skirt are both included in the leakage path. The opening between skirt and grid is 10 narrow and at right angles to the boiling movement of mercury droplets. Mercury is, therefore, unlikely to enter the inside of the skirt and form a conductive coating on the inner glass surface.

15 The conductor 15 is hollow and its lower end is flanged to afford a good connection to the grid 16. This connection is preferably welded. The conductor 15 thus forms a duct through which the tube may be exhausted. After the tube is 20 pumped, the duct may be closed by welding or if the tube is to be continually pumped during operation the duct may be kept open to the pump.

The cathode of this tube comprises a directly heated portion 20 which is connected by a lead 21 to the exterior of the tube. The portion 20 may be, as shown, a ribbon thick enough to support itself even when hot or it may be supported by a central refractory body as further described in connection with Fig. 2. In either case, it is 30 coated with emissive material. The lead 21 passes through a body 22 of glass which can seal to the metal sleeve 23 extending from the bottom 24 of the tube. The bottom 24 is welded to the part 2 and its sleeve 23 may be made of the alloy described and welded to it. If desired, the bottom 24 may be made of steel and the sleeve 23 alone of the alloy.

40 The upper end of the directly heated portion 20 is welded to a cap 25 which, in its turn, is welded to a guard 26 and this, in its turn, is welded to inwardly extending projections on a shield 27, which surrounds the guard and the directly heated portion. A surface of the guard is coated with emissive material.

45 Surrounding the shield 27 is a second shield 28 which is welded to the shield 27 by inwardly off-set portions at the top. At the bottom similar off-set portions of the shield 28 contact shield 27 but are not welded thereto. The bottom of the shield 28 has outwardly extending tabs or feet 29 by which it is secured, preferably by welding, to the plate 24. The plate 24 and the part 2 are welded together, a flange being provided on the bottom of the part 2 for securing an increased welding surface, as shown at 30.

50 The bottom of the space enclosed by the guard 26 is closed by a disc 31 of refractory ceramic material which has a flange 32 extending into contact with the interior of the shield 27. The disc 31 has a radial slot 33 which accommodates a tap 34 extending from the lower end of the part 20 through the disc 31 where it is welded to the conductor 21. This cathode structure as a 55 whole, is supported from the plate 24.

55 The function of the structure is to delay the beginning of current from the anode 1 to the cathode until the guard has had time to become sufficiently heated to emit electrons from its coated surface, as explained in greater detail in my application Serial No. 57,536, filed January 4, 1936.

70 The tubular conductor 15 and the lead 21 are coaxial with each other and with the envelope. Consequently no attention need be paid when inserting the device into its connection, to the ro-

tational position of the device with respect this axis.

In the form of my device shown in Fig. 2, the part 20, the guard 26, the shield 27 and the shield 28 function as the corresponding parts of Fig. 5 1. The tab 34 is, however, at the upper end of the part 20 and the disc 31 of refractory ceramic material is at the top of the cathode structure. The off-set portions and welds described in connection with Fig. 1 are similar in Fig. 2. There 10 are, however, some differences; the off-set portions at the top of shields 27 and 28 are not welded and no, or at most, very little heating current flows through the shields or guard. At the bottom of the cathode structure a metal plate 38 15 is provided to which each of the several cylinders of the cathode structure are welded. From the tab 34, a hollow conductor 39 extends through a bore in the center of a refractory insulator 40 to the exterior of the tube. The insulator 40 is 20 provided with staggered teeth 41 which support the individual whorls of the part 20. The top of the insulator 40 is fitted into a recess in the disc 31 which prevents relative movement between it and the other members of the cathode 25 structure. Its bottom rests upon the top of a flanged ceramic member 42.

The flange of member 42 extends from a sleeve which fits a tube 43 which extends from the center of the plate 38 to the exterior of the tube. 30 Within the tube 43 there is also fitted a glass portion 44 and a second portion 45 of ceramic insulation. The tube 43 is made of alloy which can form a sealed joint with the glass 44. The plate 38 may be made of the same alloy and it 35 and the sleeve 43 may be homogeneous, or if desired, the plate may be made of any selected metal, such as nickel, and the tube 43 welded thereto.

The envelope of the tube shown in Fig. 2 comprises an anode 46, which is essentially the shape 40 of a bell jar and has a flange at the bottom shown at 47, by which it is welded to the bottom 48. This bottom 48 has a central sleeve 49, integral therewith, or welded thereto, which is of the alloy 45 aforementioned, capable of forming a seal with the glass. Within the tube 49 is fitted a body 51 of ceramic refractory material having at its upper end, which extends beyond the tube 49 into the interior of the tube, a flange or skirt 52. The flange 52 at the top of the body 51 makes a 50 long creepage path between the cathode, which is electrically united with the sleeve 43 and the anode, which is electrically united with the sleeve 49.

55 Contacting with the bottom of the body 51 is a body 53 of glass, capable of forming a seal with the aforesaid alloy, which fits the interior of the tube 49, and contacting with the bottom of the body 53 is a thimble-like member 54 of ceramic material, the outer surface of which fits the tube 60 49. The top of the member 54 is formed into an inwardly extending flange fitted to the exterior of the sleeve 43.

The several insulating bodies 42, 44 and 45 65 have an aligned central bore through which the metallic tube 39 extends and the bodies of insulation 51, 53 and 54 have a bore to accommodate the tube 53. The two bores, the tubes 43 and 49 and all the insulating bodies are coaxial, the 70 common axis being the center of the tube 39. The exterior terminals of the anode, the cathode and the cathode heating circuit are thus three coaxial cylindrical metallic tubes.

The inner one 39 is welded shut when the 75

pumping of the device is finished and when so welded forms a peg 55 which can be the inner terminal coaxial with the exterior surface 49 and the intermediate surface 43. Nothing depends 5 on the position rotationally of the tube, but the correct contact may be made even though the tube is rotated, about its conductor 39 as an axis, to any extent whatever. This device is a rectifier and has no control electrode like the grid 16 in

10 Fig. 1.

The tube in Fig. 3 has an anode 61 which is separated from the cathode part 62 of the envelope by a seal 63. Rings of appropriate sealing metal 64 and 65 are welded to the envelope 15 portions 61 and 62 at the edges where the envelope joins the seal. The seal 63 consists of an outer portion of refractory material and an inner portion 66 of glass. This portion forms a flange on the sleeve 61. This sleeve constitutes 20 a skirt from the seal 63 adding to the length of the leakage path on the inside of the envelope between the anode portion 61 and the cathode portion 62. The outside of the seal is extended, overlapping the rings 64 and 65, and thus increasing 25 the exterior leakage path between the anode portion of the envelope and the cathode portion thereof.

In the middle of the anode portion 61 a thimble 68 is provided having a flange which contacts 30 with the exterior of the portion 61 and may be welded thereto. The inwardly extending portion 35 of the cup-shaped part of the thimble 68 is screw-threaded on its outer side which is inside of the envelope, and thus forms a threaded stud projecting into the interior of the tube. A graphite member 10 is screwed upon this stud and it is expanded into a skirt 71 which is electrically integral with the anode portion 61 of the envelope and projects nearly to the cathode. The cathode 40 is formed by a pool 72 of mercury, which rests upon the bottom of the tube and is, therefore, electrically continuous with the portion 62 of the envelope. At the middle of the bottom of the envelope a terminal 73 is provided integral 45 with the envelope portion 62.

An igniter, having a tip 75 of silicon carbide or boron carbide, is supported in contact with the pool 72 of mercury, occupies the central position in the tube. The tip 75 is supported by a screw 50 76 formed on the end of a conductor 11. The conductor is surrounded by a glass seal 78 similar to the seal 18 in Fig. 1, and ending in a skirt 79 similar to the skirt 19 in said figure. Because 55 the igniter structure is straight from the top of the device to the mercury pool, it is shorter and the structure is more rigid than it would otherwise be and because it is central there is good protection against shorting. The skirts 79 and 67 add to this protection. This position of the igniter gives a structure permitting closer spacing 60 of the electrodes and skirt. An exhaust 80 is connected, preferably by welding, by a flange 81 to the anode part 61 of the envelope which is perforated at 82 for cooperation with the exhaust. 65 The pipe 80 may be permanently connected to a pump, or when the tube has been sufficiently exhausted, may be sealed off.

If it be desired to exhaust the tube of Fig. 3 through a conductor as the tubes of Figs. 1 and 2 70 are exhausted the conductor 11 may be hollow and an opening may be made in the side thereof in the part within the skirt 79. When this is done the pipe 80 will be omitted and no hole 82 provided. When the pumping is finished the 75 tube 11 may be closed by welding or otherwise.

The skirt 78 acts to increase the leakage path from thimble 68 to conductor 11. The extension of the bottom of the thimble along the glass 78 adds to the stiffness of the structure. The recess in the thimble accommodates the external 5 part of the glass and also protects it from accidental injury. The externally extended glass also adds to the leakage path between the anode and the igniter.

When the mercury in the pool 72 is heated, 10 mercury vapor rises into the interior of the anode portion 61 of the envelope and is condensed there to a greater extent than it is condensed in the lower space because the part 62 of the envelope is a good thermal conductor in contact with the 15 pool 72. The condensed mercury, descending, forms droplets on the adjacent surfaces of anode skirt 67. The other or outer surface of the skirt 71 does not receive mercury droplets and so affords good leakage protection between the two 20 portions of the envelopes 61 and 62. The interior of the skirt 79 is well protected from droplets both by the skirt itself and because the skirt is located in a hot region. It thus affords an effective 25 prevention against leakage.

The terminal stud 13 and the conductor 11 are in line with each other and are central of the envelope. Consequently the device can be put into working relation with the external connections in any position around this axis. It is not 30 necessary to rotate the device about this axis into any particular position.

In the operation of the grid glow tube shown in Fig. 1, the element 20 is a source of electrons which are confined to the interior of the guard 35 26 until the guard has acquired sufficient temperature to cause the oxide coating thereon to emit electrons. The guard is heated by heat from the member 20 and this heat is supplied by current which enters the lead 21 and departs mainly through the outer shield 28. To some extent shield 27 may conduct the current in parallel with shield 28 but not much because the junction at the bottom is not welded. Thence the current in through the feet 29 to the bottom 24 of 40 the tube, the exterior of which constitutes at 23, the cathode terminal. The anode 1 is connected by any suitable exterior device to the positive potential. When the guard 26 has reached the proper temperature, the guard and the structure 50 55 in its interior become a source of electrons which pass to the anode. The grid 16 is controlled through the conductor 15 and when it has a sufficiently negative potential, prevents the anode current from starting.

In the rectifier shown in Fig. 2, the cathode structure acts like that described in Fig. 1, becoming a source of electrons as soon as the guard 26 has acquired sufficient temperature to emit electrons from its coated surface. Current from the anode 46 through the gas in the tube to the cathode structure is possible after this temperature is acquired, but in the opposite direction, such current is not possible. This tube, therefore, acts as a rectifier of alternating current. The connection, both to the heating circuit and to the circuit in which the current is to be rectified are made by inserting the device in its socket, no special positioning being needed as 60 65 would be with the usual plurality of connecting pins. The direct heating of the cathode member 20 in this tube is by current which enters at the exterior end of tube 39 and departs from the sleeve 43. The current to be rectified has the 70 75

sleeve 49 for one terminal and the sleeve 43 for the other terminal.

In the controlled arc device in Fig. 3, the current controlling the igniter 75 is introduced at the terminal 77 and departs through the mercury 5 12 and the cathode terminal 73. The current to be conducted by the mercury arc is between the terminal 73 and any desirable connection to the exterior of the anode 61. This current is controlled by the igniter 75 in a way familiar to those skilled in the art. It may be actuated by a dozen volts while the igniter requires some fifty 10 to one hundred and fifty volts.

Many modifications beside those specifically illustrated and described will occur to those skilled in the art, and I do not desire to be limited by the specific illustration and description of the modification shown.

I claim as my invention:

20 1. A discharge device comprising a cathode structure having a directly heated source of electrons, a lead for the heating current, a plurality of radiation shields therearound and an electrostatic guard surrounding said directly heated 25 source and separating it from said radiation shields, said shields and guard being electrically connected together by a metallic support electrically continuous with a portion of the envelope, a seal separating said lead from said portion, 30 another portion of the envelope being electrically continuous with the anode and another seal separating said portions.

2. A discharge tube comprising a metallic envelope having two portions, one of which is electrically continuous with a cathode structure having a heated source of electrons and associated metallic parts, a support for said structure extending approximately the diameter of the tube, the other said portion of the envelope being electrically continuous with the anode, a seal separating said portions and having a skirt extending into the interior of the tube, a lead for the heating circuit, a return for the heating circuit including said support, and a seal concentric with and adjacent said first-named seal between said lead and said return, whereby all external terminals of cathode and anode have the same relative position independent of the rotational position of the tube.

3. A discharge device comprising a metallic envelope having two portions, one of which is electrically continuous with the anode, the other said portion being electrically continuous with the cathode, an insulating seal separating said 55 portions and constituting a portion of the envelope, said seal having a skirt extending into the interior of the tube and providing a long leakage path on the inside of the tube between anode and cathode, and an insulating extension 60 on the outside of the seal affording a long leakage path between anode and cathode on the outside of the tube.

4. A discharge device comprising a metallic envelope having two portions, one of which is electrically continuous with the anode, the other said portion being electrically continuous with the cathode, an insulating seal separating said portions and constituting a portion of the envelope, said seal having a skirt extending into the interior of the tube and providing a long leakage path on the inside of the tube between anode and cathode, and an insulating extension on the outside of the seal affording a long leakage path 70 between anode and cathode on the outside of

the tube, a control electrode in said tube and a lead to said control electrode extending to the exterior of the envelope and a seal distinct from the first-named seal through which the lead extends.

5. A discharge device comprising a metal envelope having two portions, one of which is electrically continuous with the cathode structure, said structure comprising a source of electrons, a cylindrical guard around the source, and at least one radiation shield around said guard, said guard being electrically connected to said source of electrons at one end only, said guard being also electrically connected to one said portion of the envelope, the other said portion of the envelope being electrically continuous with the anode, and a body of insulation separating said portions of the envelope, said body of insulation having glass and ceramic materials, at least one of which forms a seal with the metal of the envelope.

6. A discharge device comprising a metallic envelope having two portions, one of which is electrically continuous with the anode structure and the other with the cathode structure, a body of insulation between said portions, said body including a part of material forming a sealing junction with the metal envelope and a part projecting from the gap between said two portions into the space within the device to form a skirt 30 materially adding to the length of the interior leakage path between the cathode and anode.

7. A discharge tube comprising a metallic envelope having two portions, one of which is electrically continuous with a cathode structure having a heated source of electrons and associated metallic parts, a support for said structure extending approximately the diameter of the tube the other said portion of the envelope being electrically continuous with the anode, a seal separating said portions and having a skirt projecting from the gap between said two portions into the interior of the tube, a lead for the heating circuit, a return for the heating circuit including said support, and a seal between said lead and said return.

8. A discharge tube comprising a metallic envelope having two portions, one of which is electrically continuous with a cathode structure having a heated source of electrons and associated metallic parts, a support for said structure extending approximately the diameter of the tube the other said portion of the envelope being electrically continuous with the anode, a seal separating said portions and having a skirt projecting from the gap between said two portions into the interior of the tube, a lead for the heating circuit, a return for the heating circuit including said support, and a seal concentric with said first-named seal, between said lead and said return.

9. A discharge device comprising a metallic envelope having two portions, one of which is electrically continuous with the anode structure and the other with the cathode structure, bodies of insulation between said portions, at least one body being of a glassy material, at least one body being of ceramic material, one of said bodies forming a sealing junction with the metal envelope and one of said bodies having a part extending within the device to form a skirt materially adding to the length of the interior leakage path between the cathode and anode.
